UNITED STATES PATENT OFFICE.

EDGAR B. SYMONS, OF CHICAGO, ILLINOIS, ASSIGNOR TO SYMONS BROTHERS COMPANY,
OF CHICAGO, ILLINOIS, A CORPORATION OF ILLINOIS

DISK FOR CRUSHING-MACHINES.

1,175,904.

Specification of Letters Patent. Patented Mar. 14, 1916.

Application filed April 26, 1915. Serial No. 22,817.

To all whom it may concern:

Be it known that I, EDGAR B. SYMONS, a citizen of the United States, residing at Chicago, in the county of Cook and State 5 of Illinois, have invented a certain new and useful Improvement in Disks for Crushing-Machines, of which the following is a specification.

My invention relates to crushing disks for 10 crushing machines and the like. It is peculiarly applicable to disks to be used in crushing machines of the rotary rocking disk type wherein the annular chamber is formed between a pair of inclined disks 15 which rotate and move one from the other to crush the material. These disks are preferably made of manganese steel or other highly resistant material which must be easily machined and it becomes necessary in 20 assembling them in the machine to use some kind of packing to prevent the expensive necessity of grinding to true them up.

In my invention I provide means for 25 holding this packing and means for holding the disk in position.

Other objects of my invention will be apparent from the specification.

It is illustrated more or less diagrammatically in the accompanying drawings, 30 wherein--

Figure 1 is a side elevation of the crushing shaft showing the crushing head and disk in section; Fig. 2 is a plan view of the back side of the disk itself. Many of the 35 parts of the crushing machine are omitted and some kindred parts are only generally shown because they do not show the subject matter of my invention.

Like parts are indicated by like letters 40 throughout the several figures.

1 is a shaft. On the end of it is a crushing head 2 having a concave or dish-like surface. Located on this crushing head and resting partially against the end of the shaft 45 and partially against the crushing head is a dish-shaped disk 3. It is held to the shaft by the cap 4 attached in position by any suitable means. The head itself is of ordinary machine steel or other suitable metal 50 and may be easily machined to give it a true conical surface. On the back side of the disk adjacent its outer periphery is an annular ring 5. This ring being comparatively narrow may be ground to a true cone 55 or circular hook to fit the conical surface

of the crushing head. Between the disk and the head and filling the space marked out by the annular ring is a packing 6 of zinc or other suitable metal which is applied in position after the disk is clamped on to the head by pouring it when in a molten state by the gate 7 left by the interruption of the ring 5 in one point in its circumference. This metal packing as it is poured in fills all the interstices between the head, the shaft and the disk to compensate for the irregularity or inaccuracy of the disk and makes a firm rigid filler for the crushing disk. 8 is a pin projecting rearwardly from the disk of such length 70 that it extends through the zinc or metal packing and penetrates into the body of the head thus acting as a key or anchor to prevent relative rotation of the head and disk.

The disk, it will be noted, is annular, 75 that is to say, it has at its center a large hole which may be engaged by the centrally located holding means. The disk is dish-shaped from this central hole outwardly, 80 but it will be observed that while both the front and rear surfaces of the disk are substantially conical, the inclination of the front surface is greater than the inclination of the rear surface and this results in a disk of constantly increasing thickness 85 outwardly.

It will be understood that as the crushing machine operates the wear is greatest about the outer periphery of the disk and it becomes desirable to so design the disk that 90 this wear may be compensated for so that as the disk wears away all parts will gradually wear down until when the disk is substantially worn out its thickness will be sub-

stantially constant. 95
The fine crushing is done at the outer periphery of the disk. There is more or less widening at that point but this increase in area is not sufficient to compensate for the increased duty of the machine at the fine crushing zone. Thus the wear is greater at the periphery and in order that there may be no sharp transition the conical surface of the disk is gradually curved outwardly 100 and bounded by a curve which varies from 105 parallelism with the conical surface at the inside to parallelism with a plane perpendicular to the axis of the disk as indicated.

I claim:

1. The combination with a dish-shaped 110

crushing disk for crushing machines and the like of an annular ring projecting upwardly from the back of the disk adjacent its periphery, said ring being interrupted 5 at one place for a short distance.

2. The combination with a dish-shaped crushing disk for crushing machines and the like of an annular ring projecting upwardly from the back of the disk adjacent 10 its periphery and a pin integral with the disk projecting rearwardly therefrom said pin being longer than the height of the ring.

3. The combination with a dish-shaped 15 crushing disk for crushing machines and the like of an annular ring projecting upwardly from the back of the disk adjacent its periphery, said ring being interrupted at one place for a short distance and a pin 20 integral with the disk projecting rearwardly therefrom said pin being longer than the height of the ring.

4. A dish shaped crushing disk for crushing machines and the like which is bounded 25 by two concentric conical surfaces, one of them being more sharply inclined to its axis than the other to form a disk whose thickness increases outwardly, one of said conical surfaces terminating in a curved

surface which is tangential to the conical 30 surface at one side and perpendicular to the axis of the disk at the other side.

5. The combination with a crushing head of a dish-shaped crushing disk supported thereon, an annular bearing ring about the 35 periphery of the disk in engagement with said head and a metallic packing contained between the head and disk and bounded peripherally by said ring, said head being recessed, a pin projecting rearwardly from 40 the disk through the packing engaging said recess.

6. The combination with a crushing head of a dish shaped crushing disk supported thereon, an annular bearing ring about the 45 periphery of the disk in engagement with said head and a metallic packing contained between the head and disk and bounded peripherally by said ring, and a pin projecting rearwardly from the disk in operative 50 engagement with the head.

In testimony whereof, I affix my signature in the presence of two witnesses this 23rd day of April 1915.

EDGAR B. SYMONS.
